UNITED STATES PATENT OFFICE.

JOHN O'CONNOR, OF CLIFTON, STATEN ISLAND, NEW YORK.

WATER-GAGE.

No. 878,992.

Specification of Letters Patent.

Patented Feb. 11, 1908.

Application filed December 2, 1907. Serial No. 404,701.

To all whom it may concern:

Be it known that I, JOHN O'CONNOR, citizen of the United States, residing at Clifton, Staten Island, in the county of Richmond 5 and State of New York, have invented new and useful Improvements in Water-Gages, of which the following is a specification.

My invention pertains to water gages for use in connection with steam boilers and 10 other water holders; and it consists in the simple, durable and efficient water gage hereinafter described and claimed.

In the drawings accompanying and forming part of this specification: Figure 1 is a 15 view, partly in elevation and partly in vertical section, of the water gage constituting the best practical embodiment of my invention of which I am aware. Fig. 2 is an elevation of the intermediate member comprised in the frame of the gage, and: Fig. 3 20 is a horizontal section taken in the plane indicated by the line 3—3 of Fig. 1, looking downward.

Similar letters of reference designate corresponding parts in all of the views of the drawings.

My novel water gage comprises a tube A, of glass or other transparent material suitable to the purpose, a frame, preferably of 30 metal, containing and holding the transparent tube, and gaskets B, preferably of rubber, surrounding and snugly receiving the end portions of the transparent tube and having for their offices to prevent the leakage 35 of water from the frame.

The tube-holding frame is made up of an intermediate member C and end members D, and, as best shown in Figs. 2 and 3, the intermediate member is provided with a longitudinal bore a of a diameter to snugly receive the tube A, interior shoulders b at the ends of the said bore a, and interiorly threaded, enlarged end portions c which are, by preference, exteriorly of angular form as 40 shown. Said intermediate member C is also provided with upright, diametrically opposite sight openings d which extend from a point adjacent to its lower enlargement c to a point adjacent to the upper corresponding 45 enlargement c and are tapered or gradually increased in width outward. By reason of the said sight openings d being arranged diametrically opposite each other, it will be observed that the height of the water in the 50 tube A may be seen by persons standing at opposite sides of the gage; and it will also

be observed that the light entering the said openings illuminates both sides of the tube A so that the height of the water may be readily seen from either side of the gage. It 60 will further be noted in this connection that the taper or gradual increase in width outward of the sight openings d is materially advantageous inasmuch as it increases the width of the range from which a person may 65 see the height of the water in the tube A. In other words by virtue of such formation of the sight openings a person does not have to stand in line with the tube but may stand at opposite sides of said line and yet distinctly see the tube and the water therein. 70

The end members D of the frame for receiving and holding the tube A are identical in construction, and for this reason a detailed description of the end member D 75 shown at the bottom of Fig. 1 will suffice to impart a definite understanding of both. The said end member D, Fig. 1, is provided with a bore m in line with that of the tube A, and an enlargement m' at the inner end of 80 bore m, and is also provided with a shoulder p arranged to abut against the end of the intermediate member C, and is further provided with a reduced and exteriorly threaded portion r which is turned into the threaded 85 enlargement c of the intermediate member C and against the lower washer B so as to crowd the said washer against the interior shoulder b of member C and thereby assure the washer or gasket snugly surrounding the 90 end portion of the transparent tube with a view of precluding leakage of water from the meeting portions of the intermediate and end frame members.

My novel gage is designed more particularly for use on steam locomotives; and it will be gathered from the foregoing description that the said gage as a whole is well adapted to withstand the excessive vibration to which the gages on locomotives are 95 ordinarily subjected. It will also be gathered that the gage is compact and durable, and that in addition to the practical advantages hereinbefore ascribed to the tapered sight openings d in the intermediate frame member 100 C, the said sight openings permit of the transparent tube A being readily seen, and yet expose but a small portion of the area 105 of the tube with the result that the liability of the tube being struck and broken is reduced to a minimum.

Having described my invention, what I

claim and desire to secure by Letters-Patent, is:

In a water gage, the combination of a transparent tube, an intermediate frame member having a longitudinal bore, of less length than the tube, snugly receiving said tube and also having interiorly threaded, end enlargements, interior shoulders at the ends of said bore and upright, diametrically-
5 opposite sight openings tapered or gradually reduced in width from the inside of the member to the outside thereof, end frame members each having a bore in line with the transparent tube and an enlargement at the
10 15 inner end of said bore snugly receiving an

end portion of the tube and also having an exteriorly threaded end portion screwed into a threaded end of the intermediate frame member, and gaskets surrounding the end portions of the transparent tube and inter- 20 posed between the interior shoulders of the intermediate member and the inner ends of the end members.

In testimony whereof I have hereunto set my hand in presence of two subscribing wit- 25 nesses.

JOHN O'CONNOR.
